(57) CLAIM

The ornamental design for a hand pruner having light permeable handles, as shown and described.

DESCRIPTION

FIG. 1 is a left profile view of a hand pruner having light permeable handles embodying my new design;

FIG. 2 is a right profile view thereof;

FIG. 3 is a top plan view thereof;

FIG. 4 is a bottom plan view thereof;

FIG. 5 is a front elevational view thereof; and,

FIG. 6 is a rear elevational view thereof.

The oblique line shading on the drawings is understood to represent a translucent or transparent surface.

The broken lines shown in the drawings are for illustrative purposes only and form no part of the claimed design.
